HANGING PLANTER

Bennie M. Wiles, 115 Carolina Ave., and Clarence P. Harris, Jr., P.O. Box 1597, both of Burlington, N.C. 27215

Filed Nov. 25, 1974, Ser. No. 526,623

Term of patent 14 years

Int. Cl. D6—04; D11—02

U.S. Cl. D35—3 A

FIG. 1 is a front perspective view of a hanging planter showing our new design;

FIG. 2 is a top plan view thereof;

FIG. 3 is a right side elevation thereof;

FIG. 4 is a bottom plan view thereof;

FIG. 5 is a perspective view of a second modified embodiment of the planter, the support member has been omitted for ease of illustration;

FIG. 6 is a top plan view thereof;

FIG. 7 is a right side elevation thereof;

FIG. 8 is a bottom plan view thereof;

FIG. 9 is a top plan view of a third modified embodiment of the planter;

FIG. 10 is a right side elevation thereof;

FIG. 11 is a bottom plan view thereof; and

FIG. 12 is a fourth modified embodiment of the planter illustrated in FIG. 1.

We claim:

The ornamental design for a hanging planter, as shown and described.
